UNITED STATES PATENT OFFICE.

ISAAC ROSENBERGER, OF TALLMAN, MICHIGAN, ASSIGNOR TO NORMAN H. BRANDENBURG, OF ASTORIA, OREGON.

DESIGN FOR A RACK OR STAND.

45,694.

Specification for Design.

Patented Apr. 28, 1914.

Application filed February 16, 1914. Serial No. 819,105. Term of patent 14 years.

To all whom it may concern:

Be it known that I, ISAAC ROSENBERGER, a citizen of the United States, residing at Tallman, in the county of Mason and State of Michigan, have invented a new, original, and ornamental Design for a Rack or Stand, of which the following is a specification, reference being had to the accompanying drawings, forming a part thereof, wherein—

Figure 1 is a perspective; Fig. 2, a side elevation; and Fig. 3, an end elevation.

I claim:

The ornamental design for a rack or stand, as shown.

ISAAC ROSENBERGER.

Witnesses:

E. P. HARNDER,
R. D. BEATTIE.
